UNITED STATES PATENT OFFICE.

MELVIN G. BAKER, OF CHICAGO, ILLINOIS, ASSIGNOR TO CHICAGO FORGING & MANUFACTURING COMPANY, OF CHICAGO, ILLINOIS, A CORPORATION OF ILLINOIS.

HOOD LATCH.

Application filed August 15, 1927. Serial No. 212,879.

My invention relates to a latching device, and particularly to a device intended for use as an automobile hood latch. One object of the invention is to provide a hood latch which, while serving to hold the hood down and closed, will also force the hood inwardly against its abutment, and will thus hold it against rattling. Another object is a provision of a latch, of the type above mentioned, which shall be cheap and easy to manufacture and simple and durable in construction. Other objects will appear from time to time in the course of the specification and claims.

I illustrate my invention more or less diagrammatically in the accompanying drawings, wherein

Figure 1 is a vertical section through an automobile hood, showing my hood latch in locking position;

Figure 2 is a plan view of the hood latch;

Figure 3 is a side elevation of the upper portion of the hood latch;

Figure 4 is an elevation of the hood latch of Fig. 3 from another side;

Figure 5 is a section on the line 5—5 of Fig. 3;

Figure 6 is a section on the line 6—6 of Fig. 3;

Figure 7 is a section on the line 7—7 of Fig. 3;

Figure 8 is a top view of the end of the tube of which the hood latch body is formed;

Figure 9 is a vertical section through a variant form of hood latch;

Figure 10 is a section on the line 10—10 of Fig. 9;

Figure 11 is a section on the line 11—11 of Fig. 9;

Figure 12 is a section along the line 12—12 of Fig. 9;

Figure 13 is a side view and Figure 14 a front view of the upper portion of the tube shown in Fig. 9; and

Figure 15 is a horizontal section corresponding to the horizontal section of Fig. 7 of the first form.

Like parts are indicated by like symbols throughout the specification and drawings.

A is a portion of an automobile frame, to which may be secured an upstanding rib or abutment member A¹, against which abuts the lower edge B¹ of the hood B when the hood is closed. Fastened to the hood B is a

member generally designated as B², which includes a downwardly and outwardly inclined cam portion B³, upwardly and outwardly inclined prongs B⁴ separated, for example, by the notch B⁵, a central portion B⁶ which is secured to the hood B, and a downwardly and inwardly turned bottom portion B⁷. B⁸ are any suitable securing members.

C is any suitable shaft or pin terminating at the bottom in the square beveled head C¹. C² generally indicates a base member having a frame engaging securing portion C³, through which may pass any suitable securing member C⁴, and the intermediate raised portion formed by the upwardly and inwardly inclined top portion C⁵ and the generally vertical side walls C⁶. C⁷ is a concave, generally spherical, flange surrounding the aperture C⁸, through which passes the pin C.

The latch body proper consists of the cylindrical member D, herein shown as rolled from a single blank and with the single axial seam D¹. About the bottom of the cylinder is an inwardly turned flange D², adapted to engage and secure the washer D³ which is loose on the shaft C. D⁴ is a washer secured to the end of the pin C, and D⁵ indicates a coiled spring compressed between the washers D⁴ and D³. The tendency of such spring is, therefore, to draw the cylinder D downwardly along the stem C.

The cylindrical member D or seamed tube D has formed at its upper end, as shown in Fig. 8, the outwardly extending lips or flanges E, E¹. These may lie in a single plane, or they may be slightly curved or arcuate in cross-section, as will be clear from Figs. 3, 4 and 5. E² generally indicates a handle member having a finger-engaging portion E³ projecting from one side and a T-lug E⁴, with a cross-bar E⁵, extending from the other. The intermediate portion E⁶ has projecting from its sides ears or flanges E⁷, which are bent about the upper end of the cylinder D, as shown in Figs. 3, 4 and 5, they being crimped or pressed inwardly beneath the outwardly extending flanges E and E¹, which may be aligned respectively with the T-lug E⁴ and the finger piece E³. When the handle member is so crimped or bent or stamped about the upper end of the tube, no soldering, welding or other securing is necessary, although if de-

sired welding may be employed as additional securing means.

G generally indicates a nose or flange member adapted to be opposed to the cam member B³. It is herein shown, as in Fig. 7, as formed of lugs projecting from the edges of the blank of which the tube D is formed. In Fig. 7 are indicated the parallel or opposed portions G¹, secured, for example, by the rivet G², and the latterly extending flanges G³, which are outwardly bent to form an extended and arcuate surface in opposition to the arcuate surface of the cam B³. Whereas I have illustrated a rivet as a securing means, obviously any other securing means at this point may be employed, and under some circumstances securing means at this point may be omitted.

Referring to the form of Figs. 9 and following, the tube H, corresponding to the tube G of Fig. 1, has a pair of opposed, outwardly extending lugs H¹, which may extend from the opposed edges of the blank where they are brought together at the seam. At the opposite side of the tube is an aperture H², herein shown as rectangular. The handle member H³ is formed with downwardly depending flanges H⁴, H⁵, which are bent to conform to the upper end of the tube, as shown in the drawings. H⁶, H⁷ are ears on said flanges, which are bent inwardly into the aperture H², as shown in Figs. 11 and 12. H⁷ is an ear on the flange H⁵ interlocking with the ear H⁸ on the flange H⁴. Referring to Figs. 9 and 10, it will be observed that the ear H⁷ penetrates beneath the outwardly projecting lugs H¹. Thus the handle is locked positively in position by the lugs H¹ at one side, and by the penetration of the ears H⁹ into the aperture H² at the other.

Figure 15 illustrates a modification of the lug nose of Fig. 7, it being understood that in actual use the form of Fig. 15 may be used in conjunction with either form of handle or tube. The lug nose of Fig. 15 is formed by a flange K outwardly projecting along the seam and upturned at its end, as at K¹. From the opposite side of the tube blank a flange K² extends along and conforms to the form of the flange K³. It is turned in the opposite direction at the outer end of the flange K, as at K⁴, and is then recurved as at K⁵, and finally lapped, as at K⁶, about the end of the portion K¹ of the flange K. When this form of lug nose is employed, no positive locking or securing of the flanges K and K² together is necessary.

It will be realized that whereas I have described and shown a practical and operative device, nevertheless many changes might be made in size, shape, number and disposition of parts without departing from the spirit of my invention. I therefore wish my description and drawings to be taken as in a broad sense illustrative and dia-

grammatic, rather than as limiting me to the specific showing herein made.

The use and operation of my invention are as follows:

In the manufacture of a hood latch of the type herein described and shown, it is extremely important to produce an article which is strong and durable and which, at the same time, consists of a minimum number of parts and which is cheap to manufacture. The hood latch herein described meets these requirements. The latch body D is a one-piece, single-seamed tube. The securing means at the bottom of the tube for holding the spring abutment D³ in place are formed integrally from the tube. The cam nose G, opposed to the cam surface B³, is formed from the same blank, being integral with the tube. I may employ the transverse pin or rivet G², as shown in Fig. 7, or I may even avoid the necessity of any additional securing member at that point by lapping the metal as shown in Fig. 15.

The handle portion or end member is a single piece, which includes the T E E⁵, the handle E³, the central portion E⁶, and the ears or flanges E⁷ which fasten the assembly together and have the additional function of keeping the seamed tube from splitting or spreading. The device is peculiarly easy to make, and in assembling the body D with the end member E is placed in a disk and a second die is brought down from above to press the end member into final position, while transversely operated dies may close the cylindrical portion of the end member, formed by the flanges E⁷, tightly against the latch body D, thus securing and attaching the end member to the body and strengthening the latch body itself.

I do not wish to be limited to any specific shaping of the blanks employed, and it will be obvious from Figs. 10 and following that a number of variations may be used.

I claim:

1. In a hood latch, a tubular body, transverse lips at one end thereof, and an end member surrounding the upper end of said body and clinched beneath said lips.
2. In a hood latch, a tubular body, an end closure member therefor secured thereto and surrounding the upper end thereof, and a handle portion associated with said end closure member.
3. In a hood latch, a tubular body, an end closure member therefor secured thereto and surrounding the upper end thereof, and inter-penetrating parts associated with said tubular body and said end member, adapted to prevent relative movement thereof.
4. In a hood latch, a tubular single-seamed latch body formed from sheet metal and a hood engaging member integral therewith and projecting laterally therefrom,

said member being formed along the seam of said body.

5. In a hood latch, a latch body comprising a one-piece longitudinally seamed tube and a cam member extending from the side of said tube, said cam member including a lug bent from the edge of the tube.

6. In a hood latch, a latch body comprising a one-piece longitudinally seamed tube and a cam member extending from the side of said tube, said cam member comprising a pair of opposed lugs outwardly extending from the opposed edges of the tube.

7. In a hood latch, a latch body comprising a one-piece longitudinally seamed tube and a cam member extending from the side of said tube, said cam member comprising a pair of opposed lugs outwardly extending from the opposed edges of the tube, the outer edges of said lugs being bent to form a relatively extended generally continuous cam surface.

8. In a hood latch, a latch body comprising a one-piece longitudinally seamed tube and a cam member extending from the side of said tube, said cam member comprising a pair of opposed lugs outwardly extending from the opposed edges of the tube, the outer edges of said lugs being bent to form a relatively extended generally continuous cam surface, one of said lugs being longer than the other and being lapped or bent thereabout.

9. In a hood latch, a latch body comprising a one-piece longitudinally seamed tube and a cam member extending from the side of said tube, said cam member comprising a pair of opposed lugs outwardly extending from the opposed edges of the tube, and

means for securing said lugs together.

10. In a hood latch, a latch body comprising a tube, lips outwardly turned from the upper edge of said tube and an end member surrounding said tube and interlocking with said lips, said end member including a hand engaging portion extending from one side thereof and a hood engaging portion extending from the opposite side thereof.

11. In a hood latch, a latch body comprising a tube, a handle member for the upper

end of said tube, said member including a handle portion and a hood engaging portion and a downward extension adapted substantially to surround the upper end of said tube.

55

12. In a hood latch, a latch body comprising a tube, a handle member for the upper end of said tube, said member including a handle portion and a hood engaging portion and a downward extension adapted substantially to surround the upper end of said tube, and means for securing said downward extension to the tube.

60

13. In a hood latch, a latch body comprising a tube, a handle member for the upper end of said tube, said member including a handle portion and a hood engaging portion and a downward extension adapted substantially to surround the upper end of said tube, and securing members outwardly extending from said tube and interlocking with said end closure member.

65

14. In a hood latch, a latch body comprising a tube, a handle member for the upper end of said tube, said member including a handle portion and a hood engaging portion and a downward extension about said tube, securing members outwardly extending from said tube, the downward extension from said handle portion being formed and bent to conform to said tube beneath said securing members.

70

15. As a new article of manufacture, a tubular body, a one piece sheet metal handle member for the upper end of the body, said member including a handle portion and a hood engaging portion and a flange downwardly bent and wrapped about the tube, and means for securing it thereto.

75

16. As a new article of manufacture, a tubular body, a one piece closure for the upper end thereof, said closure including a plurality of flanges downwardly bent and wrapped about the end of said tube and means for preventing longitudinal movement of said flanges in relation to said tube.

80

Signed at Chicago county of Cook and State of Illinois, this 10th day of August, 1927.

MELVIN G. BAKER.
